DESIGN FOR A VIOLIN OR SIMILAR ARTICLE

Arthur F. Randall and Gustavus A. Ostermeyer,
Boston, Mass.

Application March 4, 1935, Serial No. 61,464

Term of patent 14 years

To all whom it may concern:

Be it known that we, Arthur F. Randall and Gustavus A. Ostermeyer, citizens of the United States of America, residing at Boston, in the county of Suffolk and State of Massachusetts, have invented a new, original, and ornamental Design for a Violin or Similar Article, of which the following is a specification, reference being had to the drawing, forming part thereof.

In the accompanying drawing:

Figure 1 is a front elevation of a violin embodying our new design.

Figure 2 is a side elevation of the violin shown in Fig. 1.

Figure 3 is a rear elevation of the upper end portion of the violin shown in Figs. 1 and 2.

The characteristic feature of the design consists in the polygonal shaped body having a flat top, a flat back, and side walls consisting of a plurality of flat panels, as shown.

We claim:

The ornamental design for a violin or similar article, as shown and described.

ARTHUR F. RANDALL.
GUSTAVUS A. OSTERMEYER.
